US00D861652S

(12) **United States Design Patent** (10) **Patent No.:** **US D861,652 S**
(45) **Date of Patent:** **** Oct. 1, 2019**

(54) **ELECTRONIC DEVICE**

(71) Applicant: **Samsung Electronics Co., Ltd.**, Suwon-si (KR)

(72) Inventors: **Sungkwon Kim**, Seoul (KR); **Kwanue Hong**, Yongin-si (KR); **Chungha Kim**, Seoul (KR); **Giha Woo**, Seoul (KR)

(73) Assignee: **Samsung Electronics Co., Ltd.**, Suwon-si (KR)

(**) Term: **15 Years**

(21) Appl. No.: **29/600,395**

(22) Filed: **Apr. 12, 2017**

Related U.S. Application Data

(63) Continuation of application No. 29/559,965, filed on Apr. 1, 2016.

CLAIM

We claim the ornamental design for an electronic device, as shown and described.

DESCRIPTION

FIG. 1 is a front perspective view of an electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines in the figures show portions of the electronic device which form no part of the claimed design.

1 Claim, 5 Drawing Sheets
